UNITED STATES PATENT OFFICE

165,060

BUILDING

Tony M. Doram, Baltimore, Md.

Application December 4, 1950, Serial No. 13,264

Term of patent 14 years

(Cl. D13—1)

To all whom it may concern:

Be it known that I, Tony M. Doram, a citizen of the United States, residing at Baltimore city, State of Maryland, have invented a new, original, and ornamental Design for Building, of which the following is a specification, reference being had to the accompanying drawing, forming a part hereof.

Figure 1 is a plan view of a building, showing my new design;

Figure 2 is a front elevation of Figure 1; and Figure 3 is a rear elevation of Fig. 1.

I claim:

The ornamental design for a building, as shown.

TONY M. DORAM.
